UNITED STATES PATENT OFFICE.

DANIEL C. STOVER, OF FREEPORT, ILLINOIS.

SPRING-HINGE.

SPECIFICATION forming part of Letters Patent No. 391,434, dated October 23, 1888.

Application filed February 20, 1888. Serial No. 264,623. (Model.)

To all whom it may concern:

Be it known that I, DANIEL C. STOVER, a citizen of the United States, residing at Freeport, in the county of Stephenson and State of

Illinois, have invented certain new and useful improvements in Spring-Hinges, of which the following is a specification, reference being had to the accompanying drawings, in which—

Figure 1 is a plan view of a hinge embodying my improvements. Fig. 2 is a detail view of a portion of the same just before the stop engages. Fig. 3 is a cross section on the line xx , Fig. 1; Fig. 4, a perspective view of the ring or collar provided with a stop.

It is often desirable that some provision should be made whereby a door or other body swinging upon hinges shall be held open when it has been swung around to the full extent of its movement. To this end retaining-stops have been provided, fastened in some cases to the floor and in others to the side wall, which will hold the door open until they are disengaged.

My invention consists in placing this stop on a collar inserted in the hinge itself and making it a yielding stop by placing it under the pressure of a coiled spring mounted upon the hinge. It also consists in other improvements, which will be hereinafter described, and pointed out definitely in the claims.

In the forms of my invention illustrated in the drawings, A A' are the two leaves of the hinge, united in the usual manner by means of ears a a' , one of which is provided with a pin, a^2 , and the other with a corresponding eye-hole, a^3 . It is immaterial whether the pin a^2 be short or lengthened into the customary pintle. A ring or collar, B , is inserted so as to bear against one of the ears a' , and a coiled spring, C , is also inserted, pressing at one end against the face of the ring B and at the other against one of the ears a' . As shown in Fig. 1, the spring C is fastened at one end, c , to one of the leaves A' and at the other end, c' , to the collar B . The latter is provided with an inclined projection, b , which fits within a corresponding recess, a^2 , in the ear a' . It is also provided with a projection, b' , which bears against the leaf A , so that the radial tension of the spring, acting at opposite ends upon opposite leaves, operates to retain them in the

position shown in Fig. 1. The collar B is also provided with an inclined projection or cam, b^2 , and one of the leaves, A' , is provided with a corresponding notch or projection, a^3 . 55

In operation, when by opening the door the leaf A' is swung around toward the leaf A , the projection a^3 upon the leaf A' strikes against the inclined face of the stop or cam b^2 upon the ring B . As the door is swung still farther around, the axial tension of the spring C permits of the yielding of the stop b^2 , so that the projection a^3 , pressing it downward, rides over it, as shown in Fig. 2, when the axial tension of the spring C returns the collar B to place, 60 and the stop b^2 , bearing against the rear side of the projection a^3 upon the leaf A' , stops the return movement of the latter and holds the door open. When it is desired to close the door, a strong pull thereon, pressing upon the 70 collar B through the leaf A and stops a^3 and b^2 , causes the inclined face of the projection b^2 to ride downward within the corresponding inclined recess a^2 , compressing axially the spring C and bringing the collar B 75 again to the position shown in Fig. 2, so that the stop b^2 is disengaged from the leaf A' , and the latter is returned to its normal position, as shown in Fig. 1, while the axial tension of the spring C again returns the collar B to 80 place.

By placing the stop upon a collar inserted in the hinge a very important advantage is secured, inasmuch as it may be held in place by the pressure of the spring independent of any 85 pressure exerted by the weight of the door, and consequently it may be operated without the necessity of raising the door upon its hinge to enable the stops to pass each other. Moreover, this enables the stops to be so located as 90 to engage and hold the door in any required position, even to hold the door closed, when the door-casing would prevent any possible raising of the door upon its hinges.

In the employment in the various forms of 95 my invention of a spring acting against a yielding collar with a stop upon the hinge it is immaterial, so far as this part of my invention is concerned, whether or not the spring performs the additional function of unfolding 100 the leaves and closing the door by means of its radial tension, although I deem this twofold

function of the spring in my invention, as illustrated, as an additional and valuable improvement.

It is obvious that the spring C by its axial tension holds the stop b^2 in engagement with the projection a^3 , and by its further compression permits of their disengagement, whether or not the spring is under radial tension, and whether or not the opposite end of the spring 10 C is extended so as to bear against the leaf A', and whether or not the leaves are held together by the axial tension of the spring C against the ears a and a' , and whatever be the relative positions of the ears a and a' upon the leaves 15 in either of the well-known and usual forms—viz, with the ears upon one leaf both outside and upon the other leaf both inside, or with each leaf provided with one outside and one inside ear, and in both cases whether with or 20 without the employment of a pintle.

In the form of my invention illustrated in Figs. 1, 2, 3, and 4, in which a ring or collar B is employed, it is obvious that it is immaterial whether the inclined or cam surface be 25 between the projection b and the recess a^3 , into which it fits, or between the projections b^2 and a^3 , where they engage upon the rear side of each. In either case a strong pull upon the door compresses the spring and effects a dis- 30 engagement of the stops, enabling the door to be closed. Indeed, the collar B may be attached to the ear a' , or to one of the leaves, in any appropriate manner, provided it be given a partial end play against the axial tension of 35 the spring. It is also obvious that it is immaterial whether the upper face of the projection b^2 is inclined, as shown in Fig. 1, or left level and extended around the ring B under the projection a^3 , so that the position shown in Fig. 2 40 is maintained at all times, except when the projection b^2 has passed the projection a^3 , when the two stops engage, as before described. These details are mentioned to indicate the es- 45 sential feature of this portion of my invention as distinguished from that which is immaterial and subject to almost endless variation.

It is now manifest that this essential feature consists in the provision upon a hinge of stops,

one connected with each leaf, which shall come into engagement when the leaves are folded— 50 for example, by the opening of a door to which the hinge is attached—one of which stops is upon a yielding collar and is combined with a spring whose tension or pressure resists that yielding and retains the stops in engagement 55 until overcome by the application of a force greater than its tension. The essential ele- 60 ments are a yielding collar with a stop upon the hinge combined with a spring exerting its tension or pressure against the stop to resist its yielding, and this I regard as the gist of this part of my invention.

The hinge described is simple, compact, and neat in appearance, comparatively inexpensive in manufacture, and desirable in use. The 65 necessity of stops attached either to the floor or wall, always unsightly and inconvenient, is wholly obviated, while it will operate with certainty even in places where the construction and circumstances will not permit of the rising 70 of the door upon its hinges as it swings open, so that the weight of the door cannot be utilized in resisting the disengagement of the stops.

Having thus described my invention, what I claim as new, and desire to secure by Letters 75 Patent, is—

1. In a hinge, the combination, with the two leaves and their connecting-ears, of a yielding collar connected with one member of the hinge and arranged under the compression of a spring 80 and provided with a stop which engages against the other member of the hinge in any required position to retain it in that position, but which is disengaged by the application to one mem- 85 ber of the hinge of a sufficient force to effect the further compression of such spring, substan- tially as described.

2. In a hinge, the combination of the leaves A A', one of them provided with the recess a^2 upon one of its ears, the collar B, provided with 90 the projections b and b^2 , and the spring C, sub- stantially as and for the purpose set forth.

DANIEL C. STOVER.
